BAROMETER

Ira E. McCabe, Chicago, Ill.

Application July 9, 1945, Serial No. 604,076

19 Claims. (Cl. 73—386)

1

The present invention relates generally to instruments for measuring pressure and is more particularly directed to barometers of the elastic type.

It is recognized that a membrane of an elastic substance secured at the edges will be deformed if the pressure on one side exceeds that on the other. This is the principle underlying the operation of the elastic barometer wherein elastic deformation of some solid system is magnified by a lever arrangement and utilized as an indicator of atmospheric pressure.

There are two main types of elastic barometers, namely, the Bourdon and the aneroid. The Bourdon barometer comprises a curved tube of elliptical cross section, partly or fully evacuated. Changes in atmospheric pressure effect changes in the radius of tube curvature. One end of the tube being fixed, the motion of the free end in response to atmospheric pressure variations is amplified by a system of levers to indicate the extent of the pressure.

Fundamentally, the aneroid barometer consists of an enclosed chamber of thin metal, partly or fully evacuated. When constructed of very thin material, spring means are employed to prevent the chamber from collapsing under the external pressure of the atmosphere. At a predetermined pressure, equilibrium will be established between the force of air and the spring. In practice, the chamber is usually made thin and flexible so that the elastic properties of the spring determine those of the entire instrument. Aneroids, however, when formed and made of heavier materials of sufficient strength require no spring loading and may constitute the available commercial forms, contemplated for use in the structures hereinafter described.

In elastic barometers heretofore known, a number of factors contribute to impair the accuracy and sensitivity of the instruments, such as lag, mechanical hysteresis, friction and lost motion in the moving parts, and elastic errors due to changes in ambient temperature.

Accordingly, it is the primary object of this invention to provide an elastic barometer of the Bourdon or aneroid type characterized by a high order of accuracy and sensitivity. It is also an object of this invention to provide a barometer of the above type wherein lost motion and friction in the moving parts are eliminated. An additional object of this invention is to provide a barometer of the above type which is of simple, rugged and compact construction.

Broadly stated, the objects of this invention

2

are fulfilled by a cooperative arrangement between an atmospherically sensitive, elastic element and a cross-spring pivot structure, said arrangement acting in a manner whereby the movement of the element is imparted to the spring pivot to obtain a scale reading either by deflecting a pointer mounted on the pivot along a scale or rotating a mirror incorporated in a mirror amplifier. By mounting a movable contact on the spring pivot and engaging said contact with an electrical commutator block, a barometric switch is provided for radiosonde applications.

For a better understanding of this invention, as well as other objects and features thereof, reference is made to the following detailed description to be read in connection with the accompanying drawing wherein:

Figure 1 illustrates in plan view a preferred embodiment of a Bourdon type barometer in accordance with the invention;

Figure 2 is a side view taken in the direction of A—A of Figure 1;

Figure 3 shows the barometer of Figure 1 as it appears when expanded under low atmospheric pressure;

Figure 4 is a detail of the cross-spring pivot of Figure 1;

Figure 5 is a fragmentary view of the scale employed in the barometer of Figure 1;

Figure 6 is a preferred embodiment, illustrated in plan view, of a second Bourdon type barometer in accordance with the invention;

Figure 7 is an end view taken along the line B—B of Figure 6;

Figure 8 is a third preferred embodiment of an aneroid barometer in accordance with the invention;

Figure 9 is an end view taken along the line C—C of Figure 8;

Figure 10 is a preferred embodiment of an aneroid barometer of the type employed with radio recording, barometer, balloon ascension apparatus and including the features of the invention;

Figure 11 is a side view of the cross spring pivot structure incorporated in the embodiment described in Figure 10, when the contact member is at the midpoint of its operable swing; and

Figures 12A, B, C and D show the movable contact member in the barometer of Figure 10 in various positions when the aneroid is contracted and expanded.

Referring now to the drawings and more particularly to Figures 1, 2, and 3, wherein like components are designated by like numerals, there is

shown a barometer comprising a pair of arcuate-shaped Bourdon tubes 10 and 11, mechanically coupled to a cross-spring pivot 12, adapted to rotate a mirror 13 mounted thereon, a barometric scale 14, a light source 15 to illuminate said scale and a viewing telescope 16 trained on said mirror whereby the angular position of the mirror with respect to the scale furnishes a magnified pressure reading. The instrument is housed within a suitable casing indicated by dashed line 17, with the eye-piece of telescope 16 extending without said casing.

Bourdon tubes 10 and 11 are each secured at one end to a cylindrical post 18 mounted on a rectangular block 19. Means are provided for shifting the position of block 19, said means including a setscrew 20. Bourdon tubes 10 and 11 are evacuated through a nozzle 21 communicating with both tubes within post 18.

The cross-spring pivot 12 is a form of elastic hinge comprising a system of four identical pairs of flat springs 22 connecting three generally square frames 23, 24, and 25, the end frames 23 and 25 being supported in the condition of equilibrium by the said pairs of springs 22 at equi-spaced and corresponding parallel positions with respect to center frame 24. The springs of each pair 22 are arranged in spaced relation to intersect as in the letter X, and they serve to connect the center frame 24 with the end frames 23 and 25, the springs being fastened at the opposite end portions of the vertical arms of the frames, as may be seen most clearly in Figure 2.

The center frame 24 may be separately viewed in Figure 4 and it will be seen that a transverse piece 26 is connected between the horizontal arms of the frame at the midpoints thereof and supports mirror 13 in a central position perpendicular to the plane of the frame. A segment of the front vertical arm of center frame 24 is removed to fully expose the face of mirror 13 to the view of telescope 16.

Bourdon tube 10 is linked to pivot 12 by means of a suitably shaped rigid wire 27 affixed at one end to the midpoint of the lower horizontal arm of frame 25 and at the other end to a lug 28 attached to a free end of tube 10. Likewise, Bourdon tube 11 is linked to pivot 12 by means of a suitably shaped rigid wire 29 affixed at one end to the midpoint of the upper horizontal arm of frame 23 and at the other end to a lug 30 attached to the free end of tube 11.

The characteristic of the cross-spring pivot 12 is such that the center frame 24 rotates about the axis of transverse piece 26 when the end frames 23 and 25 are laterally displaced by the movement of Bourdon tubes 10 and 11 in response to variation in atmospheric pressure. The direction of displacement depends on whether the pressure is rising or falling. One such condition is demonstrated in Figure 3 where it will be seen that Bourdon tubes 10 and 11 are expanded as a result of low pressure thereby laterally displacing end frames 23 and 25 outwardly in opposite directions, as indicated by the arrows, to rotate mirror 13.

The pivot system is perfectly elastic since there are no moving parts in contact to produce friction; also its construction enables it to withstand a sudden reversal of load which might unseat other types of pivots. Moreover, since there are no moving parts in frictional contact, lag is minimized, no lubrication is necessary and no wear takes place. The barometer components are preferably fabricated of metal having a sub-

stantially zero temperature coefficient so that no error will be introduced by reason of thermal changes.

The scale 14 is vertically attached to an adjustable base 31 having an arcuate slot 32 formed therein permitting adjustment of the scale position within the limits defined by the slot. Although scale 14 is of relatively short length, the markings inscribed thereon, as depicted in Figure 5, are designed to enable a wide range of millibar graduations. Scale 14 is formed by evenly spaced vertical lines 33, indicating progressive steps of ten millibar intervals, which are connected by diagonal lines 34, each diagonal connecting two adjacent vertical lines at opposite extremes thereof. Diagonal lines 34 are divided by eleven evenly spaced horizontal lines 35, into ten equal parts, each of the eleven horizontal lines at the point of intersection with a diagonal line 34 registering one millibar. Thus a scale of short length provides a wide range of graduation without crowding of indicia. This scale design is especially useful for barometers of compact construction.

In viewing the reflection of the scale 14 through telescope 16, the telescope hairline sight, when aligned either with a particular intersection of a horizontal line 35 and a diagonal line 34 or a particular vertical line 33, will at that time register the millibar reading for the pressure being recorded.

It will be seen, therefore, that the combination of cross-spring pivot 12 and mirror 13 behaves as a balanced amplifier for the movements of Bourdon tubes 10 and 11 in that a slight displacement of the mirror effects a relatively large shift in the position of the telescope hairline with respect to scale 14.

The calibration of the instrument is accomplished against a standard gauge by orienting the scale 14 and block 19 to a position whereby the scale readings correspond with that of the standard.

Referring now to Figure 6 there is shown in plan view another preferred embodiment of a Bourdon type barometer in accordance with the invention, and to Figure 7 there is shown said barometer in end view as seen along the line B—B in Figure 6. The instrument comprises a single Bourdon tube 36 mounted at its midpoint and having both free ends mechanically coupled to respective end frames 37 and 38 of a cross-spring pivot 39. The cross-spring pivot 39 is identical with the pivot 12 discussed in connection with Figure 1 except for the center frame 40 which is adapted to support an indicator 41 comprising two parallel supporting bars 42 attached to the center frame 40, said bars supporting at one end a pointer 43 which rides along an arcuate barometric scale 44. Pointer 43 is counterbalanced at the other end of supporting arms 42 by a weight 45 which serves to maintain proper balance and stability.

Referring now to Figure 8 there is shown in plan view another preferred embodiment of my invention in the form of an aneroid barometer, and to Figure 9 showing said barometer in end view as seen along the line C—C in Figure 8. The instrument comprises a pair of evacuated aneroid chambers 46 and 47, mechanically coupled to a cross-spring pivot 48, rotating a mirror 49 mounted thereon. As in the instrument disclosed in Figure 1, the aneroid barometer includes a scale and a viewing telescope operating in conjunction with mirror 49, but since these

components have already been shown in connection with Figure 1, they are not again reproduced.

The cross-spring pivot 48 is identical with the pivot 12 disclosed in Figure 1 except that the mirror 49 is secured below the center frame 50 coplanar therewith thereby clearing the mirror face of all obstructions. The aneroid chambers 46 and 47 are maintained in parallel relation, each being bolted on one side to a suitable supporting frame. The free side of aneroid chamber 46 is linked to the end frame 51 by a rigid wire 52, while the free side of aneroid chamber 47 is similarly linked to end frame 53 by supporting wire 54. The concurrent expansion or contraction of aneroid chambers 46 and 47 in response to atmospheric pressure causes a lateral displacement of end frames 51 and 53 of the pivot resulting in rotation of mirror 49. Rotation of mirror 49 provides a barometric reading in the same manner as described in connection with Figure 1.

Referring now to Figure 10, a preferred embodiment of a radio recording, barometric balloon ascension apparatus incorporating the present invention is shown as comprising, essentially, a U-shaped frame, a pair of evacuated aneroid chambers mechanically coupled to a cross spring pivot structure swinging a movable electrical contact member along an electrical commutator block having a series of contacts adapted to be contacted by the movable contact member.

The legs 55 and 56 of the U-shaped bracket 57 support, upon the inner side of each, toward their free ends, evacuated aneroid chambers 58 and 59, respectively. Coupled, by means of the screws 60 to mounting pins 61 and 62 concentrically attached to their respective aneroids 58 and 59, is a cross spring pivot structure 63, which sustains and actuates a movable electrical contact member 64. At the base of the U bracket 57 a commutator block 65 is secured and provided with a series of contacts whereby the same, when incorporated into the electrical circuit of a radio transmitting system, with the contact member 64, provides a means of registering changes in altitude as expansion and contraction of the aneroids move the contact member over the contacts of the commutator block 65.

The cross spring structure as shown in Figures 10 and 11, when in the state of equilibrium, maintains a pair of base plates 66 and 67 in parallel relation with a pivot plate 68, the facing surfaces of the said base plates and the pivot plate serving as supports for connecting thereto the ends of the cross springs 72, 73, 75, 76. Pivot plate 68 serves as a common support for all the spring ends terminating on one side of the cross spring arrangement and also as a support for the movable electrical contact member 64. The two base plates 66 and 67 are movable, independently of each other, and are connected to their respective aneroid chambers 58, 59, to be moved thereby, by angular extensions 69 and 70. The base plates 66 and 67 serve as supports for the other ends of the cross springs.

As may be seen in Figure 11, base plate 67, connected to the aneroid chamber 59, is adapted for movement through a cutout portion 71 at the center of base plate 66. The spring structure connecting the base plate 67 to the pivot plate 68 comprises two spaced-apart springs 72 centrally located between two springs 73, the inner springs 72, arranged in relation to the outer springs 73, to provide an intersection as at 74, like the letter X, as shown in Figure 10.

As may be seen in Figures 10, and 11, base

plate 66, attached to aneroid chamber 58 is tied to the pivot plate 68 by two pairs of springs 75 and 76, each pair arranged in the form of the letter X and located, one pair on each side of the opening 71.

As heretofore mentioned, the pivot plate 68 also serves as a support for the movable contact member 64. As viewed in Figure 10, a right angle extension 77 provides a means to connect, by a cross spring pivot structure 78 identical with that formed by springs 72 and 73, the base 68 and contact member 64 to provide a resilient and flexible juncture.

To compensate for variations in expansion between different sets of aneroid chambers, over the same pressure change range, the connecting extension 70 to aneroid chamber 59 may be provided with an arcuate slot through which the screw 60 may secure the extension to the aneroid. By shifting the base plate 67 so that the intersection 74 is moved closer to, or further from, intersection 79, according to the amount of expansion provided by the aneroid chambers, adjustment can be made to provide sufficient movement of the movable contact 64 over the full scale with the available movement of the aneroids.

Referring to Figure 10, the free extremities of the U bracket 57 are joined together by a connecting rod 80. The rod is threaded at each end, one of the threads being of smaller diameter and finer than the other. The ends of the bracket are threaded to receive on one side the coarse-threaded end of the rod and the other the fine-threaded end. Upon proper assembly the rod may be turned to widen or narrow the distance between the aneroids and thereby cause movement of the contact 64 to establish the zero or starting contact point for a predetermined pressure condition.

Referring to Figures 12A to D there is shown in detail, the position of the movable contact 64 when the aneroid is contracted and expanded. Figures 12A and B show the amount of movement necessary to cover the scale with the extension 70 bolted to the aneroid 59 as shown in Figure 10, Figure 12A illustrating the condition with a contracted aneroid and Figure 12B with an expanded aneroid. Figures 12C and D show the smaller amount of movement needed of the aneroids to cover the scale, when the base plate 67 is shifted upwardly and bolted to the aneroid 59 at the bottom of the slot, Figure 12C illustrating the condition with a contracted aneroid and Figure 12D with an expanded aneroid.

Thus, there has been shown in several preferred embodiments elastic barometers wherein the movement of the sensitive element or elements is amplified without the use of gears or other moving components introducing lost motion, backlash, friction or other mechanical defects inherent in instruments of the prior art.

While there have been described what are at present considered preferred embodiments of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. The combination in an elastic barometer comprising atmospherically sensitive elastic means; of a cross-spring pivot including three

frames, one of which is pivotable and is coupled to each of the other two by a pair of crossed springs, so that the pivotable frame is caused to pivot upon movement of the other two frames relative to each other; means for imparting the movement of said elastic means to at least one of said last mentioned two frames; and means responsive to the rotation of said pivotable frame to obtain a barometric scale reading.

2. The combination in an elastic barometer comprising a pair of Bourdon tubes, both affixed at one end; a cross-spring pivot structure, said structure including a pivot frame, two base frames and cross-springs connecting said pivot frame to each of said base frames; means coupling the free ends of said Bourdon tubes to said base frames respectively whereby they cooperate to rotate said pivot frame; and means responsive to the rotation of said pivot frame to obtain a barometric scale reading.

3. The combination in an elastic barometer comprising a pair of Bourdon tubes, both affixed at one end; a cross-spring pivot structure, said structure including a pivot frame, two base frames and cross-springs connecting said pivot frame to each of said base frames; means coupling the free ends of said Bourdon tubes to said base frames respectively whereby they cooperate to rotate said pivot frame; a barometric scale; and a pointer mounted on said pivot frame as to be rotated along said scale.

4. The combination in an elastic barometer comprising a pair of Bourdon tubes, both affixed at one end; a cross-spring pivot structure, said structure including a pivot frame, two base frames and cross-springs connecting said pivot frame to each of said base frames; means coupling the free ends of said Bourdon tubes to said base frames respectively whereby they cooperate to rotate said pivot frame; a mirror mounted on said pivot frame so as to rotate therewith; a telescope, having a hairline sight, trained on said mirror; a barometric scale having graduations so disposed with respect to said mirror as to be viewed in said telescope, whereby the scale graduation coinciding with said hairline provides a scale reading.

5. The combination in an elastic barometer comprising a pair of Bourdon tubes, both affixed at one end; a cross-spring pivot including a generally rectangular center frame, a pair of generally rectangular end frames disposed at opposite sides of said center frame, four pairs of flat springs, each pair arranged in spaced relation to intersect as in the letter X and connecting respectively said end frames with said center frame at the upper and lower portions of the vertical arms thereof; means rigidly linking the free ends of said Bourdon tubes to said end frames as to laterally displace said end frames in opposite directions in accordance with the movement of said tubes; and means responsive to the rotation of said center frame to obtain a barometric scale reading.

6. The combination in an elastic barometer comprising a pair of Bourdon tubes, both affixed at one end; a cross-spring pivot including a generally rectangular center frame, a pair of generally rectangular end frames disposed at opposite sides of said center frame, four pairs of flat springs, each pair arranged in spaced relation to intersect as in the letter X, and connecting respectively said end frames with said center frame at the upper and lower portions of the vertical arms thereof; means rigidly linking the free ends

of said Bourdon tubes to said end frames so as to laterally displace said end frames in opposite directions in accordance with the movement of said Bourdon tubes; a mirror mounted on said center frame to rotate therewith; a telescope, having a hairline sight, trained on said mirror; a barometric scale so disposed with respect to said mirror as to be viewed in said telescope whereby the scale marking coinciding with said hairline provides a scale reading; and means to illuminate said scale.

5 7. The combination in a cross-spring pivot comprising a generally rectangular center frame; a pair of generally rectangular end frames disposed at opposite sides of said center frame; and four pairs of flat springs, each pair arranged in spaced relation to intersect as in the letter X and connecting respectively said end frames with said center frame at the upper and lower portions of the vertical arms thereof, whereby lateral displacement of said end frames in opposite directions causes rotation of said center frame.

20 8. The combination in an elastic barometer comprising a Bourdon tube affixed intermediate its ends; a cross-spring pivot structure, said structure including a pivot frame, two base frames and cross-springs connecting said pivot frame to each of said base frames; means coupling the free ends of said Bourdon tube to said base frames respectively whereby they cooperate to rotate said pivot frame; and means responsive to the rotation of said pivot frame to obtain a barometric scale reading.

25 9. The combination in an elastic barometer comprising a pair of aneroid cells; a cross-spring pivot structure including a pivot frame and two sets of cross-springs connecting said frame to said cells respectively whereby they cooperate to rotate said pivot frame, and means responsive to the rotation of said pivot frame to obtain a barometric scale reading.

30 10. The combination in an elastic barometer comprising atmospherically sensitive elastic means; of a cross-spring pivot structure comprising a pivotable member and two relatively movable members coupled respectively to said pivotable member by two pairs of cross springs and also coupled to said elastic means whereby they cooperate to rotate said pivotable member, and means responsive to the rotation of said pivotable member to obtain a barometric scale reading.

35 11. The combination in an elastic barometer comprising atmospherically sensitive means; a cross-spring pivot structure comprising relatively movable members coupled to said elastic means, a pivot member and cross-springs between said pivot member and each of said movable members whereby operation of said means causes rotation of said pivot member, indicating means responsive to the rotation of said pivot member to obtain a barometric scale reading and means to adjust the coupling between at least one of said movable members and said atmospherically sensitive means to vary the amplitude of movement of the indicating means in accordance with the movement obtainable from said sensitive means.

40 12. The combination in an elastic barometer comprising a pair of aneroid cells; a cross-spring pivot structure including a pivot member and two sets of cross-springs respectively coupling said member to said cells whereby they cooperate to rotate said pivot member, a commutator including a series of electrical conductors, a movable contact, and means responsive to the rotation of

said pivot member to move the contact over the conductors in engagement therewith.

13. The combination in an elastic barometer comprising a pair of aneroid cells; a cross-spring pivot structure including a pivot member, two relatively movable members and two sets of cross-springs connecting said pivot member to said movable members respectively, said relatively movable members respectively being coupled to said cells whereby they cooperate to rotate said pivot member, a commutator including a series of electrical conductors, a movable contact, and means responsive to the rotation of said pivot member to move the contact over the conductors in engagement therewith.

14. The combination in an elastic barometer comprising a pair of aneroid cells; a first cross-spring pivot structure including a pivot member, two relatively movable members and first and second sets of cross-springs connecting said pivot member to said movable members respectively, said relatively movable members respectively being coupled to said cells, whereby they cooperate to rotate said pivot member, a commutator including a series of electrical conductors, a movable contact and a third set of cross-springs coupling said pivot member to said contact, whereby rotation of the pivot member moves the contact over the conductors in engagement therewith.

15. The structure of claim 13 wherein means are provided for adjusting the relative positions of said movable members, to vary the amplitude of movement of the contact, in accordance with the movement obtainable from the cells.

16. The structure of claim 14 wherein means are provided for adjusting the relative positions of said movable members, to vary the amplitude of movement of the contact, in accordance with the movement obtainable from the cells.

17. The combination in an elastic barometer comprising a pair of aneroid cells; a U bracket supporting one of said cells upon the inner face of each leg adjacent the free ends thereof, a commutator adjacent the opposite end thereof including a series of electrical conductors, a cross-spring pivot structure including a pivot member, two relatively movable members and first and second sets of cross-springs connecting said pivot member to said movable members respectively, said relatively movable members being coupled to said cells whereby they cooperate to rotate said pivot member, a movable contact, a third set of cross-springs, coupling said pivot member to said contact, whereby rotation of the pivot member

moves the contact over the conductors in engagement therewith and means for adjusting the free ends of the bracket relative to each other to adjust the contact to its initial position.

18. The structure of claim 17 wherein means are provided for adjusting the relative positions of said movable members, to vary the amplitude of movement of the contact, in accordance with the movement obtainable from the cells.

19. In a barometer, the combination of a cross spring pivot structure, the said pivot structure including a pivot frame member, first and second auxiliary frame members spaced from said pivot frame member, a first pair of crossed springs

joining the pivot frame member to the first auxiliary frame member, and a second pair of crossed springs joining the pivot frame member to the second auxiliary frame member, whereby said pivot frame member is rotated upon movements of the auxiliary frame members relative to each other; and pressure-sensitive means including first and second terminals movable relative to each other in response to variations in pressure, said first and second terminals being coupled respectively to said first and second auxiliary frame members, so that movement of said terminals relative to each other causes movement of said auxiliary frame members relative to each other; and means to indicate the position of rotation of the pivot frame member.
